STOP MOTION MECHANISM

Charles W. Arrowood, Charlotte, N. C.

Application July 31, 1946, Serial No. 687,449

4 Claims. (Cl. 66—163)

1

Some of the objects of the invention having been stated, other objects will appear as the description proceeds, when taken in connection with the accompanying drawings, in which—

Figure 1 is a side elevation of the stop motion apparatus with portions broken away;

Figure 2 is a vertical sectional view taken along the line 2—2 and showing the parts in the position when normal tension is applied to the yarn;

Figure 3 is a vertical sectional view taken along the line 3—3 in Figure 1 and showing the parts in the same position as shown in Figure 2;

Figure 4 is a view similar to Figure 2, but showing the parts in operative position, with increased tension applied to the yarn;

Figure 5 is a view similar to Figure 4, but showing the parts in the position they will occupy when too great a tension is being applied to the yarn, such as by its hanging up on the cone and not properly shedding from the cone;

Figure 6 is a vertical sectional view taken along the same line as Figure 3, but showing the parts in the position they will occupy when too great a tension is present in the yarn as it comes from the cone;

Figure 7 is a top plan view of the apparatus shown in Figure 1 with a portion thereof in section;

Figure 8 is a detail looking down on the top of Figure 5 and showing how the thread rides outwardly to release the stop motion drop wire.

Referring more specifically to the drawings, the numeral 10 indicates an arm or bracket, which is usually attached to the uprising shaft of the cone and tension rack on a knitting machine. The cones of yarn are disposed on suitable arms on the rack below the level of the arms 10 and suitable guide arms having eyes therein are disposed above the brackets 10 through which the yarn is passed, after passing through the first portion of the apparatus and going through the second portion, after which it goes through a suitable guide eye and tensioning means and sometimes a moistening apparatus on its way to the feed fingers of the knitting machine.

There would be an arm 10 for each stop motion switch on the machine, and there would be a stop motion mechanism for each strand of yarn being employed in the knitting machine. Arm 10 has an eye 11 near its outer end through which the yarn or strand 12 passes in its upward travel.

Secured on the upper side of arm 10 is an

uprising member 13 which projects laterally at its upper end, as at 14, and has a slot 15 therein. Mounted in the uprising member 13 is a bolt 16 having slidably and loosely mounted thereon movable tension discs 17 and 18 normally pressed against collar 19 by means of a compression spring 20.

The bolt 16 has surrounding the same a porcelain sleeve 21 on which the tension discs 17 and 18 are loosely and slidably mounted and these tension discs have an opening therein of greater diameter than the sleeve 21, so that they can not only slide but have swinging movement on the sleeve 21. The outer end of bolt 16 is threaded and has threadably mounted thereon a pair of nuts 23 and 24 for regulating the compression present in spring 20 for regulating the amount of pressure applied to the tension disc 18, one nut 23 serving to regulate this tension and the nut 24 is really a lock nut for locking the nut 23 in position.

Also uprising from arm 10 is an uprising member 27. Rotatably mounted in members 13 and 27 is a shaft 30 having an upturned portion 31 immediately to the right of member 13 in Figure 1, which has an inturned portion 32 near its upper end and a laterally and outwardly or horizontally projecting portion 33 which is adapted to have movement into and out of slot 15 in projection 14. The shaft 30 has a collar 37 adjustably secured thereon and having extending therefrom a screw and contact member 38. This contact member 38 is adapted at times to engage a fixed contact 39 secured on a binding post 34 mounted in an insulating sleeve 35 disposed in arm 10. The arms 10 are grounded, forming one side of an electrical circuit and binding post 34 has secured thereto a wire 36 forming the other side of the circuit, said circuit leading to a suitable stop motion, signal light, alarm bell and the like. Wire 36 would necessarily lead to the stop motion apparatus of the machine and could also lead through suitable alarm mechanisms or signalling mechanisms as desired.

Oscillatably mounted in the members 13 and 27 is a shaft 40 having an outturned portion or arm 42 provided with a hook 43 on one end. The other end of shaft 40 has an uprising curved end portion 44 adapted at times to move in between the tension discs 17 and 18 and relieve the tension on the yarn or strand when it becomes hung on the cone or fails to be fed freely. Also oscillatably mounted in brackets 13 and 27 is a shaft 50 having an uprising portion 51 and a lat-

erally projecting portion 52 and an angular end portion 53. Near its other end the shaft 50 has a collar 55 secured thereon provided with an arm 56 to which the lower end of a tension spring 57 is secured, the tension spring projecting upwardly and passing through a horizontal portion 58 of member 27. Portion 58 has pivotally mounted as at 60 a swingable blade member 61, which is adapted to enter the folds of tension spring 57 at any desired point to regulate the tension present in spring 57.

This shaft 50 has a laterally projecting arm 62 which passes through loop portion 43 and then projects upwardly and then downwardly forming a broad notch 64 through which the strand of yarn passes after it is passed through the apparatus on the right hand side of Figure 1, and after it has gone through a suitable guide eye disposed thereabove.

Method of operation

As before stated, there is an arm 10 for each strand of yarn being knitted in the knitting machine, and the yarn or strand 12 is passed up between the tension discs 17 and 18 and in front of the horizontally projecting portion 33 of upturned portion 31, which prevents the horizontally projecting portion 33 from going through the slot 15. The yarn thus holds the parts in the position shown in Figures 1 and 2 and it goes up through a suitable eye and back under the flat V-shaped portion of arm 62 and then goes upwardly again through another guide eye on its way to the feed fingers of the machine. This holds the parts in the position shown in Figure 3, and Figures 4 and 7 also show the parts in normal operating position. Now, in case a strand 12 breaks and allows the horizontally projecting portion 33 to swing through slot 15 and occupy the position shown in Figure 5, which will cause the uprising contact 38 to move over against fixed contact 39 to close the circuit to operate the stop motion mechanism of the machine and also to give a suitable signal or alarm if desired. In other words, the contact 38 will move over to the position shown in Figure 6. Now, while the yarn is running under normal tension, the parts will be in the position shown in Figure 4, that is, the end portion 44 on shaft 40 will be moved in between the tension discs 17 and 18 a slight amount, not far enough to spread them apart. Now, in case the let-off of the yarn from the cone is hindered in any way, and there is greater tension on the yarn than normal, the arm 62 will be raised upwardly from the position shown in Figure 3 to the position shown in Figure 6, which will cause the portion 44 to move in between the tension discs 17 and 18 and relieve the tension on the yarn. In case the tension is not relieved, the pull of the yarn will cause it to move outwardly on the angular end portion 53 of portion 52 and will thus push the yarn or strand from between the projection 14 and portion 33 and free it from the portion 33 and allow the portion 33 to pass through slot 15 and allow shaft 30 to oscillate and swing to the position shown in Figure 5, which will cause contact to be made between contact screw 38 and the fixed contact 39 and stop the machine.

In the drawings and specification, there has been set forth a preferred embodiment of the invention, and although specific terms are employed, they are used in a generic and descriptive sense only, and not for purposes of limita-

tion, the scope of the invention being defined in the claims.

I claim:

1. A stop motion mechanism through which a strand of yarn is adapted to be passed, comprising an uprising fixed member having a laterally projecting portion provided with an open ended slot, a second uprising member disposed in spaced relation to the first uprising member, a shaft oscillatably mounted in the two uprising members and having an upturned portion provided with a horizontal projecting portion adapted to move through said slot, and having a contact member near its other end, a fixed contact adjacent the contact on the shaft, a pair of tension discs on the first uprising member, through which a strand of yarn is adapted to be passed, said strand of yarn being adapted to be passed between the lateral projection on the first uprising member and the horizontally projecting portion on the first named shaft, a second shaft oscillatably mounted in the uprising members and having an uprising portion adapted to pass between the tension discs and having at its other end an outturned portion, a third oscillatable shaft mounted in the uprising members and having portions bent to project above a lateral projection on the first named uprising member and having an outwardly and angularly directed member against which the yarn is adapted to contact on its upward travel, excessive tension in the yarn causing it to move out the laterally and angularly extending portion on the third named shaft to push the yarn from between the horizontally projecting portion on the first named shaft and the laterally extending portion on the first uprising member to allow the first named shaft to oscillate, the fixed contact being adapted to be contacted by the contact on the first named shaft to close a circuit and stop the machine with which the stop motion is associated, parting of the yarn allowing the first named shaft to oscillate to cause its contact to engage the fixed contact to also close the circuit and stop the machine, movement of the yarn out the angularly extending portion of the third named shaft tending to oscillate the second named shaft to relieve tension on the yarn by having its uprising curved end portion moving in between the tension discs.
2. A stop motion device adapted to have a strand passed therethrough and to be affixed to a suitable machine processing the strand comprising an electrical circuit, having a contact, an oscillatable shaft having a contact thereon, normal tension on the strand serving to hold the oscillatable shaft in a position to where its contact will not engage the fixed contact, a pair of tension disks, a second oscillatable shaft having means on one end for passing between the tension discs to relieve tension on the yarn and having a laterally extending portion on its other end, a third oscillatable shaft having a portion on one end adapted to engage a strand, and having an arm on its other end adapted to engage the arm on one end of the second named shaft, excessive tension in the yarn serving to guide the strand out of contact with the arm on the first named shaft to allow it to oscillate to cause its contact to engage the fixed contact to stop the machine and excessive tension on the arm on the third named oscillatable shaft serving to move the second named oscillatable shaft to cause the uprising curved end portion on one

end thereof to pass between the tension discs to relieve excessive tension on the yarn.

3. Stop motion means through which a strand of yarn is adapted to be passed and having an electrical circuit provided with a fixed contact, an oscillatable shaft having a contact thereon adapted to engage the fixed contact, means on the first-named shaft for engaging the yarn to hold the shaft in a position to where its contact will not engage the fixed contact, a second oscillatable shaft, a pair of tension discs through which the yarn is passed, a portion on one end of the second shaft passing in between the tension discs for relieving tension on the yarn, the second shaft having an arm on its other end, a third oscillatable shaft having an uprising portion on one end provided with a sloping surface adapted to engage the strand as it passes through the apparatus, the third shaft having an arm on its other end passing below the arm on the other end of the second shaft, excessive tension on the yarn serving to cause the portion on the first end of the second shaft to pass between the tension discs to decrease the tension on the yarn and also serving to guide the yarn off of the first arm on the first named shaft to release the yarn from the first named shaft to allow it to oscillate to cause its contact to engage the fixed contact to close a circuit to stop the machine with which the apparatus is associated.

4. A stop motion apparatus to be associated with a knitting machine and the like, comprising an arm, a pair of vertically disposed or uprising members disposed in spaced relation on said arm, first, second and third shafts oscillatably mounted in said vertically disposed members, the first of said vertically disposed members having a lateral projection provided with a slot near its upper end and having a pair of tension discs mounted thereon, the yarn being adapted to be 40

passed through the tension discs and adjacent the laterally projecting portion on the first vertically disposed member, the first shaft having an upturned portion on the end thereof provided with a horizontal portion and adapted to pass through said slot in the lateral projection on the first named vertically disposed member and the passage of the yarn being adapted to prevent the first shaft from oscillating, the second named shaft having an uprising, curved end portion on one end thereof adapted to pass between the tension discs and having a laterally projecting arm on its other end, the third shaft having an upwardly projecting arm adjacent the first upturned portion and having a sloping portion thereon adapted to contact the yarn adjacent the point where it is contacted by the laterally projecting portion on the first arm, the third shaft having an arm on its other end adapted to be passed below the arm on the other end of the second shaft, and beneath which the strand of yarn is adapted to be passed so that increased tension on the yarn will cause the uprising curved end portion on the first named end of the third shaft to pass between tension discs to relieve the tension of the yarn when it is above normal, the sloping portion on the first named arm on the second named shaft guiding the yarn outwardly when excessive tension appears to push it from contact with the laterally projecting portion on the upwardly projecting arm on the first shaft to allow it to pass through the slot in the horizontally projecting portion on the first vertically disposed member to allow the first named shaft to oscillate by gravity to cause its contact to engage the fixed contact to stop the machine, and tension means on the third shaft for pressing its sloping portion into engagement with the strand of yarn.

CHARLES W. ARROWOOD.
